UNITED STATES PATENT OFFICE.

JOHN FRANCIS KENNEDY, OF BALTIMORE, MARYLAND, ASSIGNOR TO DELION TIRE AND RUBBER COMPANY, OF BALTIMORE, MARYLAND, A CORPORATION OF MARYLAND.

ADJUSTABLE BANDING-BOARD.

1,397,763.

Specification of Letters Patent.

Patented Nov. 22, 1921.

Application filed September 21, 1921. Serial No. 502,302.

To all whom it may concern:

Be it known that I, JOHN F. KENNEDY, a citizen of the United States, residing at Baltimore, in the State of Maryland, have invented certain new and useful Improvements in Adjustable Banding-Boards, of which the following is a specification:

This invention relates to certain new and useful improvements in what are known as banding boards upon which rubber strips are manufactured into bands, and it more especially relates to a board of the character indicated, mounted so as to be capable of rotatable movement and thus facilitate the making of the comparatively thin, wide rubber bands necessary to form the plies to be used in that part of pneumatic tires immediately adjacent the outer layer of canvas or other foundation fabric forming the casing.

As heretofore constructed it has been necessary in the manufacture of such bands either to have a number of machines each for a different size band, or one machine with a number of band boards of different lengths which were capable of being detachably mounted upon or demounted from a single machine.

One of the objects I have in view is to overcome the present disadvantages and loss of time necessary to mount or demount the band board from the frame upon which it is located whenever a change in size is necessary. This I do by providing a board adapted to be readily adjusted or extended to different lengths so that but one board will be necessary for the manufacture of different sized bands.

Another object of my invention is to provide means whereby such board will hold positively and steadily at its different extended lengths and will also be equally as solid and capable of withstanding the hard usage to which it is necessarily subjected at any extended point, as it is when in its unextended position.

With these and other objects in view which may be incident to my improvements, the invention consists in the parts and combinations to be hereinafter set forth and claimed, with the understanding that the several necessary elements comprising my invention, may be varied in construction, proportions and arrangement, without de-

parting from the spirit and scope of the appended claims.

In order to make my invention more clearly understood, I have shown in the accompanying drawings means for carrying the same into practical effect, without limiting the improvements in their useful applications to the particular constructions, which for the purpose of explanation, have been made the subject of illustration.

In the accompanying drawings: 65

Figure 1 is a side view of my improved device.

Fig. 2 is a plan view thereof.

Fig. 3 is a view showing the construction in detail of the wheel for rotating the band board and the means for locking the said board in rotative position. 70

Fig. 4 is an enlarged perspective view of the extension or insert block.

The numeral 1 refers to the bottom or bed plate of a metallic frame from which extend upwardly at each end side pieces 2, which are connected together by a metallic top plate 4, the side and top plates preferably being cast integral with the bottom plate 75 and the latter being provided with several apertures through which bolts extend to secure it to the floor or bed block.

Secured upon the top plate 4 by bolts 4' is a journal block 5 in which is mounted 85 a shaft 6 with a collar 7. The outer end of the shaft is squared so as to fit in the end of a detachable crank in order that the shaft 6 may be readily turned thereby, should it become hard to turn through neglect to 90 oil the same. The numeral 9 refers to the hub of a wheel 9' which is mounted upon the shaft 6. This wheel has spokes 11 connecting the hub with the rim 12, the periphery of which is provided with teeth 13. The 95 object of the shaft 6 is to support the sleeve board 14 and said shaft extends transversely through the board and extending parallel therewith are supplemental supporting rods 15 one end of each of which is screwed into 100 one of the spokes 11 and the other end of which extends through a hole in the sleeve board.

In order to insure that the supporting shaft and the supporting rod shall fit 105 tightly within the sleeve board and not slip when the board is turned, they are made square in cross-section, as are likewise the

holes through which they pass, the outer ends of each of the rods being provided with a winged nut or thumb screw 16 whereby the board may be drawn up tightly 5 against the wheel 9' located on the opposite side.

Mounted upon the top plate 4 adjacent the journal box 5 and forming an integral extension thereof is a hollow block 20 and 10 within the block and surrounding a rod 21 extending therethrough is a spiral spring 22 one end of which is attached to the rod 21 and normally presses said rod in the direction of the arrow. This rod 21 is provided 15 with a knob 22 at one end, by means of which it may be pulled in the opposite direction. The other end of the rod 21 is enlarged as at 23 to provide for a plunger 24 at one end of which is a knob 25 and whose other end is 20 cut upon a diagonal line, (as more clearly seen in Fig. 3), to fit between the teeth 13 on the periphery of the wheel 9' and lock its movement in one direction. This plunger is also surrounded by a spiral spring 28. The 25 diagonal edge permits the wheel with a slight effort to be readily turned in one direction even when the edges of the plunger lies between the teeth but locks it against reverse movement. By turning the plunger, however, so that its diagonal edge will be oppositely disposed to that shown, the wheel is 30 locked from turning in the opposite direction.

The numeral 14 refers to the sleeve board 35 which is of rectangular configuration in cross section; one end is squared off as at 31 and the other end is rounded off as at 32. The interior of the sleeve board is hollowed out as indicated in the dotted lines 33 (see Fig. 40 2), and adapted to fit therein and to slide in and out, is an extensible and adjustable board 34. It will be observed, however, that the extensible member 34 is considerably smaller than the board within which it fits 45 being approximately of the size of the hollowed out portion of the latter.

The outer end of the extensible member is provided with an end board 35. This board on its inner face 36 is of the same superficial 50 area in cross section as the banding board proper and its outer face is of rounded contour to correspond with the other end 32 of the sleeve board. Attached to one side of this end board 35 is a metallic adjusting strip 37, which is secured thereto by bolts or otherwise. The strip is provided for the greater portion of its length with a slot 38 so as 55 to permit such slotted end to readily slide over a stationarily mounted worm shaft 39 projecting from the side of the sleeve board. Upon the shaft is a worm wheel 40 adapted to travel upon the worm shaft 39 and adapted to push the metallic strip 37 tightly 60 against the sleeve board and hold it at any 65 point which may be selected for adjustment.

The reference numeral 41 indicates an insert block to be used in connection with the banding board. It is of the same shape and size in cross section and is interiorly reamed out as seen in Fig. 4, so as to enable it to 70 slide over the extensible member 34.

It is proposed to have a number of interchangeable insert blocks, each of a different length, through any one of which the extensible member is adapted to be slipped until the insert block is in contact with the end board 35, when the extensible member is pushed in the opening in the sleeve board. One face of the block then contacts with the sleeve board and the other face with the 80 end board. The end board is then pushed firmly down against the insert block and the adjusting wheel brought tightly against the metallic strip 37, so as to hold firmly and tightly in place the end board and the interposed insert block between it and the banding board. 85

In this way the end board 35 rests upon a perfectly solid and firm foundation upon which the strips of rubber may be cut, laid 90 out and worked into shape.

It will be understood that the sleeve board and the several units to be used therewith, can be readily moved in one direction by the workman simply pushing against it while 95 engaged in his work. Should he desire to move the board in the opposite direction, the spring operated plunger between the teeth 27 must either be withdrawn or reversed in position. The bands in the making extend 100 around one end of the sleeve board to the other and back again and the workman turns the board as the work progresses, and when he desires to make bands which are longer or shorter than those he is working on, the 105 proper length of board is readily obtained by means of the interchangeable insert blocks as above indicated, and the adjusting strip and wheel.

While I have shown and described the preferred embodiment of my invention, I wish 110 it to be understood that I do not confine myself to the precise details of construction herein set forth, by way of illustration, as it is apparent that many changes and variations may be made therein, by those skilled 115 in the art, without departing from the spirit of the invention, or exceeding the scope of the appended claims.

I claim:

1. A device of the character described comprising a supporting shaft and supplemental supporting rods coöperating therewith, an extensible sleeve board stationarily mounted thereon, a frame in which the other 125 end of the shaft is journaled, and means which will permit the rotation of the shaft and board.

2. A device of the character described comprising a supporting shaft, an extensible 130

- and adjustable sleeve board stationarily mounted thereon, a frame in which the other end of the shaft is journaled, and means to permit the rotation of the shaft and board.
- 5 3. A device of the character described comprising a supporting shaft, a hollow sleeve board stationarily mounted thereon, an extensible member adapted to slide within said board, a frame in which the other 10 end of the shaft is journaled, and means to permit the rotation of the shaft and board in one direction and to lock it against rotation in the other direction.
4. A device of the character described 15 comprising a supporting shaft, a hollow sleeve board stationarily mounted thereon, an extensible member adapted to slide within said board, means to adjust the extensible member at any desired point, a frame in 20 which the other end of the shaft is journaled, and means to permit the rotation of the shaft and board in either direction and to lock it against rotation in the other direction.
- 25 5. A device of the character described comprising a supporting shaft, a hollow sleeve board stationarily mounted thereon, an extensible member adapted to slide within said sleeve board, an insert block adapted 30 to be interposed between the end board and the sleeve board, means to lock the extensible member at any predetermined point, a frame in which the other end of the shaft is journaled, and means to permit of the 35 rotation of the shaft and board in one direction and to lock it against rotation in the other direction.
6. A device of the character described comprising a supporting shaft, a hollow sleeve board stationarily mounted thereon, 40 an extensible board adapted to slide within the sleeve board, an end board on the extensible board, a sliding adjusting strip one end of which is adapted to be firmly held at any predetermined point against the sleeve 45 board, an insert block adapted to be interposed between the end board and the sleeve board, a frame in which the other end of the shaft is journaled and means to permit the rotation of the shaft and board in one 50 direction, and locking means to hold it against rotation in the other direction.
7. A device of the character described comprising a supporting shaft, supplemental supporting rods coöperating therewith, a 55 hollow sleeve board stationarily mounted upon said supporting shaft and supplemental supporting rods, an extensible member adapted to slide within said board, an end member on the extensible board, an adjusting strip one end of which is attached to the end board and the other end of which is slotted and adapted to be firmly held by an adjusting wheel against the sleeve board, interchangeable blocks of different lengths 60 adapted to be interposed between the end board and the sleeve board, a frame in which the other end of the shaft is journaled, and means to permit the rotation of the shaft and board in one direction and locking 65 means to hold it against rotation in the other direction.

In testimony whereof I affix my signature.
JOHN FRANCIS KENNEDY.
